UNITED STATES PATENT OFFICE.

EMIL JACOBSEN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed February 11, 1918, Serial No. 216,452.

To all whom it may concern:

Be it known that I, EMIL JACOBSEN, a citizen of the United States of America, and a resident of Chicago, Cook County, and State of Illinois, have invented certain new and useful Improvements in Automatic Telephone Systems, of which the following is a specification.

My invention relates in general to improved circuits and apparatus for use in automatic telephone systems or in semi-automatic telephone systems in which automatic switches are controlled by a subscriber or operator to establish connections.

More specifically my invention relates to improved switches and apparatus for use in that type of system where party or polystation lines are employed, and where different frequencies are connected to a party line to signal the various stations thereon.

In a party line system in which it is desired to make the party lines of a system accessible to local and long distance calls it has heretofore been the common practice to use the well known frequency selecting connector switch which responds first to one digit of the called number to elect a group of lines, then to a second digit to connect with the desired line in the group, and lastly to a third digit which is used to operate an auxiliary frequency selecting switch to select the desired frequency.

In a great number of systems it is required that, when an operator seizes a connector by means of her toll selector switch and finds the called line busy, she may leave the connection set up until the line goes idle, when the connector switch will cut in and ring. Now in attempting to use a switch in which the last digit is used to select the frequency it was found that very often the operator, after the line became idle, either neglected to call the last digit to select the frequency or else had by that time forgotten the frequency which was needed for the desired station.

Among the objects of my invention, therefore, is the provision, in a switch which is used for both local and long distance connections, of means whereby the first digit delivered to the connector selects the frequency desired and the last two digits select the called line terminals. In this manner the difficulties above pointed out will be over-

come, as when a line is found busy, the frequency will already have been selected, and the only further operation required when the line becomes idle, is for the switch to automatically connect the selected ringing current to the called line.

In the drawings, I have shown an operator's toll selector E (Fig. 1), having access to a toll frequency selecting connector H (Fig. 2) which in turn has access to a plurality of party lines similar to that in which the substation A is one of the stations. I have shown the substation A as busy in a local connection having its individual line switch C connected to a trunk line. The connector H is also multipled into the banks of a plurality of local selectors (not shown) which may be of any well known two wire type. Associated with the connector H is an auxiliary frequency selecting switch I, which is used to select the desired frequency of ringing current.

I will now point out more in detail the method of operation involved when an operator attempts to establish a connection with the line of substation A while said line is busy, and also the results which occur when said line becomes idle.

The operator first inserts the calling plug of her cord circuit into the jack X of the selector E, thereby closing, at the springs 2, the operating circuit from her cord circuit through the springs 3 and 4, and relay 5, to battery. The relay 5 will immediately energize over this circuit from ground through the usual calling device in the sleeve conductor of the cord circuit, and, upon energizing, closes a circuit for the slow relay 6 from ground through springs 8 and 9, and relay 6 to battery. The relay 5 also closes a high resistance shunt circuit about the condenser 10 which is connected between a pair of the windings of the repeating coil, said circuit extending from the upper side of condenser 10, springs 11, lower winding of relay 12, and resistance 13 to the lower side of the condenser. The closure of this shunt circuit however has no effect at this time as the talking circuit is still open at the springs 14 and 15. The energization of the slow relay 6 over the previously traced circuit supplies a ground to the supervisory circuit through springs 19 and 20 to light the busy lamp 16 and others which may be multipled

therewith; grounds the upper winding of the electropolarized relay 12, which relay, however, is arranged so that it will not operate its armatures unless the current flowing in both windings is in the same direction; and also prepares a circuit from the back contact of relay 5 through the series slow relay 16 and the vertical magnet 17 at the springs 18.

Now when the operator's calling device is operated for the first digit of the called number, the circuit of the line relay 5 is thereby interrupted a corresponding number of times. Each time the relay 5 deenergizes, it closes a circuit from ground through springs 8 and 21, springs 61, springs 18, relay 16, and vertical magnet 17 to battery. The vertical magnet 17 operates in response to this series of impulses to lift the wipers to some level of the banks to which connector switches, having access to a desired group of lines, are connected. Although the circuits of relays 6 and 16 are interrupted momentarily at each operation of relay 5, both will remain energized during transmission of such impulses and, after the impulses cease and relay 5 comes to rest energized, the relay 16 will fall back and relay 6 will remain energized. As soon as the vertical magnet operates, to raise the shaft and wipers one step, the off-normal springs 25 and 26 close. The springs 26 close the circuit of release magnet 27 at one point and the springs 25 close a point in the circuit of the rotary interrupter relay 28. The circuit of release magnet 27 is maintained open at the back contact of relay 6. The relay 28, however, energizes as soon as the springs 25 close, over a circuit extending from ground through springs 19 and 20 of relay 6, springs 29 and 30 of relay 16, springs 25, and relay 28 to battery. The relay 28, upon energizing, closes a locking circuit for itself at the springs 31 extending from ground through springs 7, springs 31, interrupter springs 32 of rotary magnet 33, springs 25, and relay 28 to battery, and also closes one point in the circuit of the rotary magnet 33 at springs 34. Now after the impulses for the first digit cease and the relay 16 deenergizes, a circuit is closed for the rotary magnet extending from ground through springs 19 and 20, springs 29 and 35, springs 34, and magnet 33 to battery. The rotary magnet 33 therefore operates to step the wipers 22, 23 and 24 one step onto the first set of contacts in the bank level before which it stands. Another result of the operation of the rotary magnet is to open the locking circuit of the relay 28 at springs 32. The relay 28 will therefore deenergize and open the circuit of the rotary magnet at springs 34 and also open a contact in its own locking circuit at springs 31. As soon as the springs 34 open, the rotary magnet will de-

energize and again close springs 32. Assuming now that the trunk line selected is busy, a ground potential will be found on the private contact with which the wiper 24 is now in contact. As soon, therefore, as the springs 32 come into contact, a new circuit will be closed for the relay 28 extending from ground over the wiper 24, springs 36 and 37, springs 32, springs 25, and relay 28 to battery. The relay 28 will again operate to close the circuit of magnet 33 and its own locking circuit, the said magnet operating to step the wipers to the next contact. This alternate operation of the relay 28 and rotary magnet 33 continues until an idle trunk line is reached, at which time no ground will be found upon the private contact and the relay 28 will therefore remain deenergized after the springs 32 are closed. It may be here noted that, during the energization of the relay 16 and also during the rotation of the wipers, the relay 38, although in series with the relay 28, is maintained short circuited, first, by the ground through springs 19, 20, 29, and 30 and during rotation by the ground on the private wiper. The last mentioned short circuit extends from ground on wiper 24, springs 36 and 37, relay 38, springs 20 and 19 to ground. Now, however, when an idle trunk is reached, this short circuit is removed and the relay 38 which is of high resistance energizes in series with relay 28. The circuit for energizing this relay extends from ground through the springs 19 and 20, relay 38, springs 32, springs 25, and relay 28 to battery. The relay 28 does not energize over this circuit on account of the high resistance of the winding of relay 38. The relay 38, upon energizing, extends the talking circuit from the windings 39 and 40 of the repeating coil to the wipers 22 and 23, and also prepares a locking circuit for itself through the springs 36 and 41' which will be supplied with ground from the switch ahead as will be pointed out. Another result of the energization of relay 38 is to remove ground from the springs 31 of relay 28 by opening the springs 7, and to open the circuit of the vertical magnet 17 at the springs 61 to prevent further operation thereof, thereby preventing any further operation of the operating magnets.

Now as soon as the relay 38 closes its springs 14 and 15, a circuit is thereby established for the line relay 41 of the connector H through the windings of the differentially wound relay 42. The relay 42 does not operate at this time as the magnetic fields set up by the current flow in its two windings neutralize each other. The circuit for relays 41 and 42 extends from battery through the upper winding of relay 41, springs 43 and 44, upper winding of relay 42, wiper 22, springs 14, winding 39 of the repeating coil, springs 11, lower winding of

relay 12, resistance 13, which may be approximately 200 ohms, winding 40 of repeating coil, springs 15, wiper 23, winding of relay 42, springs 45 and 46, and lower winding of relay 41 to ground. The relay 12 of selector E does not energize at this time as the current in its two windings flows in opposite directions. The line relay 41, upon energizing, closes the circuit of slow relay 52 through the springs 53 and 54, which relay, upon energizing, connects ground to the release trunk through springs 47, to render the switch busy to other calls and also to supply an additional ground to the holding circuit of relay 38 (Fig. 1). This same pair of springs also closes a circuit for the upper winding of the slow acting ring cut-off relay 48, said circuit extending from ground through springs 47, resistance 49, wiper 50 of the frequency selecting switch, and upper winding of relay 48 to battery. The springs 55 closed at this time have no effect, while the closure of the springs 56 and 57 prepares a circuit for the motor magnet 58 at one point. The relay 48, upon energizing, attracts its armature to close a number of spring contacts, only one, however, having any effect at this time, that being the springs 59 and 60 which operate to close a second contact point in the circuit of magnet 58. Now when the operator sends out the second digit of the called number, the line relay 5 of selector E will be operated as in the previous digit to attract and retract its armatures a predetermined number of times. The closure of springs 8 and 21 has no effect at this time due to the springs 61 being held open by relay 38. The opening and closing of springs 11, however, opens and closes the circuit, previously traced, of the line relay 41 of the connector H. The relay 41 each time it retracts its armature closes a circuit for the motor magnet 58 extending from ground through the springs 53 and 62, springs 56 and 57, off-normal springs 63 and 64, springs 59 and 60, springs 65, and magnet 58 to battery. The magnet 58 operates in response to this digit to step the wipers 50 and 51 to a certain set of contacts, thereby selecting the desired frequency of ringing current to which the wanted subscriber's bell is tuned. It will be seen that, as soon as the wiper 50 leaves its first or normal position, the previously traced circuit for the upper winding of relay 48 is opened. This relay is maintained in energized position however during the operation of magnet 58 by the operation of the springs 66 which intermittently applies ground to said circuit. The relay 48 being slow acting will therefore maintain its armatures attracted until the magnet 58 ceases its operation, at which time the relay 48 will deenergize and open the initial energizing circuit of the magnet 58, which can not again be closed because of the wiper 50 being in advanced position. Assuming the second digit to have been 3, then the wipers 50 and 51 will be left standing in third position with the generator R connected to the ringing lead 67.

The operator will now operate her calling device for the next or third digit, thereby operating the line relay 5 a corresponding number of times to in turn operate the line relay 41. The relay 41, in response to the impulses of this digit, again operates to open and close the springs 53 and 62. The relay 48 having fallen back, the vertical magnet 70 will be operated in place of the motor magnet 58. The circuit of the vertical magnet extends from ground through springs 53 and 62, springs 56 and 57, springs 63 and 64, springs 59 and 68, slow relay 69, and vertical magnet 70 to battery. The vertical magnet will be operated a number of times to step the wipers 71, 72, and 73 to a group or level of trunk lines in which the terminals of the desired line are located. Upon the first vertical step of the wipers, the off-normal springs 63 and 64 are opened and spring 63 comes into contact with spring 74, and the springs 75 are closed. Although the circuit for the vertical magnet is opened by the springs 63 and 64, a new circuit has been prepared in the meanwhile by the operation of relay 69, which circuit extends from ground through springs 53 and 62, springs 56 and 57, springs 63 and 74, springs 76 and 77, and over the previously traced circuit through the vertical magnet. It may be noted that the slow relay 52 remains energized during the entire operation of the line relay regardless of the momentary deenergizations thereof, and that the relay 69 remains energized constantly during the vertical series of impulses. Now when the relay 41 comes to rest energized after the impulses to the vertical magnet cease, the relay 69 will deenergize, opening its own circuit at the springs 76 and 77, and closing, at the springs 76 and 78, a point in the circuit of the rotary magnet 79 and also of the slow relay 80. Now when the line relay 41 is again operated in response to the fourth or last digit, through the medium of the line relay 5 of selector E, the rotary magnet 79 is operated to rotate the wipers 71, 72, and 73 to the terminals of the desired line. The circuit of the rotary magnet extends from ground through springs 53 and 62, springs 56 and 57, springs 63 and 74, springs 76 and 78, springs 81, springs 82 and 83, and rotary magnet 79 to battery. A branch of this circuit extends from the springs 81 through the slow relay 80 to battery so that relay 80 and magnet 79 are energized in multiple. The relay 80 energizes upon the first impulse and closes the springs 84, thereby short circuiting the springs 81 of relay

85 and maintaining the circuit of itself and magnet 79 closed irrespective of the condition of relay 85 during this series of impulses. Another result of the energization 5 of the slow relay 80 is to close a point in the circuit of the busy or test relay 85, at the springs 86 and 87. The relay 80, being slow acting, will maintain the springs 86 and 87 closed for a brief interval after the 10 line relay has come to rest and connection has been made with the terminals of the desired line.

Assuming the called line to be busy because of some call being extended therefrom, as shown, the private contact will be grounded. Before the springs 86 and 87 are opened, therefore, a circuit will be completed for the busy relay 85, extending from ground to the wiper 73, springs 86 and 87, 15 relay 85, springs 65, and magnet 58 to battery. The relay 58 will not energize in series with relay 85 which is of high resistance. The relay 85, however, energizes to close a locking circuit for itself which is 20 closed as soon as relay 80 falls back and extends through springs 87 and 99, springs 96 and 91, springs 90 and 89, and springs 47 to ground. Relay 85 also opens the initial energizing circuit for the rotary magnet and relay 80 at springs 81, closes a shunt or short circuit about the lower winding of slow relay 42 at springs 97, and connects the secondary winding of the busy machine M with the lower talking conductor, thereby 25 giving the operator a busy signal.

The short circuit which was thus established about the lower winding of relay 42 causes said relay, whose windings are differential, to be energized, thereby switching 30 the locking circuit of the busy relay 85 to the wiper 73. This new circuit extends from ground at wiper 73, springs 98 and 90, springs 91 and 96, springs 99 and 87, relay 85, springs 65, and magnet 58 to battery. 35 It will be seen, therefore, that the relay 85, instead of being permanently locked, remains energized only as long as the called line is in use and until the ground is removed from the private contact thereof.

As soon as the ground disappears from 40 the private wiper 73, the relay 85 will de-energize and restore its springs to normal. The shunt being removed from the winding of relay 42 by the opening of springs 97, 45 said relay will deenergize after a brief interval and close one point in the circuit of relay 88. The circuit for relay 88 is now complete and extends from ground through springs 47, springs 89 and 90, springs 91 and 92, lower winding of relay 88, springs 93 and 86, private wiper 73, relay 94 of line switch C, and magnet 95 to battery. Relays 50 98 and 94 energize over this circuit, relay 94 being mechanically adjusted so as to attract its armatures only half way when the

line relay 100 is not energized, will therefore operate to disconnect the relay 100 and ground from the called line. Relay 88, upon energizing, closes a locking circuit for its upper winding through springs 101, opens 70 the circuit of magnet 58, and places a direct ground on the wiper 73 to maintain the called line busy and also to short circuit its own lower winding. Another result of the energization of relay 88 is the closure of the 75 springs 102 and 103, thereby connecting ringing current to the called line. The ringing circuit extends from battery through the upper winding of relay 48, springs 104 and 105, springs 102, wiper 71, to and through 80 the ringer of substation A, and back through wiper 72, springs 103, springs 106 and 107, to spring 108. The spring 108 is controlled by the common interrupter relay 109 to connect the above traced ringing circuit alternately to battery and to the generator R through wiper 51, which now stands in third position. As long as the receiver of the 85 called station remains on the hook, the ringer thereat will be operated intermittently and the relay 48 will remain deenergized being non-responsive to alternating current. When the receiver is removed in response to the signal, a direct current circuit will be established for said relay 48 which will immediately energize to disconnect the ringing lead from the circuit of the called line by opening the springs 107 and 106 and to connect the talking circuit from the condensers 110 and 111 to the wipers 71 and 72. The energization of relay 48 connects the ground from springs 112 through springs 113 to close a locking circuit for its own lower winding and also connects said ground to the lower winding of back bridge relay 114. The 90 springs 105 and 106, upon engaging their front contacts, close a circuit for the back bridge relay 114, extending from ground through springs 112, springs 113, lower winding of relay 114, front contact of spring 106, springs 103, wiper 72, through the talking equipment of substation A, and back through wiper 71, springs 102, spring 105 and its front contact, and upper winding 95 of relay 114 to battery. The relay 114 energizes over this circuit and operates the springs 115 and 116 and the associated contacts to reverse the connections of line relay 110 114 to the talking circuit, and to short circuit the windings of relay 42. This causes a reversal of current in the talking circuit to the lower winding of the electro-polarized relay 12 of the selector E. The relay 12, now having both windings assisting each other, 115 operates to close the circuit of relay 120 at springs 121. The relay 120, upon energizing, opens the circuit of relay 122 at springs 123 and closes a new circuit for the lower winding of relay 12 at springs 124, and replaces the relay 6 directly in the operating 120 130

circuit of the operator in place of relay 5 which now deenergizes. The closure of springs 125 at this time closes the series circuit for a supervisory signal at the operator's cord circuit to control the usual operator's signal to notify the operator that the called man has answered and also short circuits the relay 122. The springs 117 are also closed by the relay 114 to maintain the connecting relay 88 energized in case the calling man should hang up first to maintain the connector operated, and the springs 118 are opened by relay 114 to maintain the circuit of release magnet 119 open until the called man hangs up.

Conversation may now proceed over the heavy conductors shown in the drawing and when the conversation is completed, the connector may be released by either the operator or called man; that is, by the operator or the called party depending upon which one disconnects last, while the selector E is restored by the operator only. Should the calling subscriber hang up first, the operator will remove the plug from the jack X and thereby open the circuit of the relay 6 at the jack. The relay 6, upon deenergizing, closes an energizing circuit for the release magnet 27 and opens the holding circuits of relays 38 and 12. The selector E is thereupon released and in releasing opens the circuit of line relay 41 of connector H. The relay 41, upon deenergizing, opens the circuit of relay 52. The deenergization of these two relays prepares a circuit for the release magnet 119 which is held open at springs 118 of back bridge relay 114. The connector H is prevented from being seized by another selector switch, while it is maintained in an operated position by the called subscriber having his receiver off the switch-hook, by a ground potential on the test contact of the associated trunk line, this ground being supplied from the springs 120 on the connecting relay 88. As soon as the called subscriber hangs up his receiver, the switch will be released in the usual manner by the release of relay 114 and the subsequent operation of release magnet 119. Should the called subscriber have hung up his receiver first, the relay 114 would deenergize to close the springs 118 and to again operate the supervisory signal in the operator's cord circuit by means of relays 12 and 120 of selector E, after which the operator would withdraw the plug to deenergize relay 41 and release the switches in the usual manner.

When the operator is calling a subscriber in the manner pointed out, it is often necessary for the operator to re-ring the called subscriber either because the called subscriber hangs up too soon or because the operator has another call waiting for the

same subscriber. In this case, the operator will press the usual ringing key to connect generator out over her cord circuit and through the windings of a special tuned relay 122 (Fig. 1). The relay 122 will not be short circuited by the springs 125 at this time, as relay 120 will be deenergized when the called subscriber hangs up. The relay 122, upon energizing, closes the springs 126 to short circuit one winding of the relays 42 and 41 (Fig. 2). This short circuit extends from ground through springs 126, winding 40 of the repeating coil, springs 15, wiper 23, lower winding of relay 42, springs 45 and 46, and lower winding of relay 41 to ground. The relay 42 being differential will energize at this time to open the springs 112, which springs control the ground connection to ring cut-off relay 48. The relay 48 will therefore deenergize to again close the previously traced ringing circuit for the called station, after which, the relays are operated in the usual manner when the call is answered to disconnect the ringing circuit and conversation may again take place over the talking circuit shown.

It will be seen therefore that I have provided a very efficient system of calling a party line subscriber from an operator in which the frequency desired is selected before the line is selected so that in a system in which the connection is cut through after a busy called line becomes idle, the called subscriber will be signaled immediately without further operation by the operator and in which, although automatic ringing is used to signal such subscriber, the operator may at any time re-ring the called subscriber's bell.

Having fully ascertained and described my invention, what I claim to be new and desire to have protected by Letters Patent, will be pointed out in the appended claims.

What I claim as my invention is:

1. In a telephone system, a plurality of generators, each supplying current of different frequency, a party line, a plurality of stations on said party line each having a signal responsive to current from one of said generators, a switch for connecting with said party line, another switch individual to said first switch but having a separate wiper shaft, means for operating said other switch in response to one of the digits of the called number to select one of said generators, and for thereafter operating said first switch in response to a plurality of digits of said called number to connect said first switch with said party line and to apply the selected generator thereto for signaling one of the stations thereon.

2. In a telephone system, a plurality of sources of alternating current, each supplying current of different frequency, a line,

- 6
- an automatic switch having vertical and rotary motion for connecting with said line, an auxiliary switch associated with said automatic switch and operable independently thereof for selecting one of said sources of current, means for delivering a plurality of series of impulses to said automatic switch, and means whereby the first of said series of impulses operates said auxiliary switch to 5 select a source of current and the others of said series of impulses cause said automatic switch to move in a vertical and rotary motion to connect said selected source of current to said line.
- 10 15 3. In a telephone system, a line, an automatic switch, a plurality of sources of ringing current, an auxiliary switch associated with said automatic switch and operable independently thereof for selecting one of said sources, means for sending a plurality of series of impulses to said automatic switch for first operating said auxiliary switch to select one of said sources and for thereafter operating said automatic switch 20 25 in response to a plurality of series of impulses to find said line and connect said selected source of ringing current therewith.
4. In a telephone system, a party line, an operator's cord circuit, an automatic switch, 30 a plurality of sources of ringing current, a plurality of stations on said line each responsive to current from only one of said sources of current, means for making said called line busy, means controlled by said operator for operating said switch to first 35 select one of said sources of current and then connect said automatic switch with said line while busy, means controlled by the busy condition of said line for preventing the 40 establishment of a talking connection with said party line, means for automatically establishing a talking connection with said line when it is again idle, and means controlled by the idle condition of said line for 45 connecting said selected source of ringing current therewith.
5. In a telephone system, a party line, an operator's cord circuit, an automatic switch, a plurality of sources of ringing current, a 50 plurality of stations on said line each responsive to current from only one of said sources of current, means for making said called line busy, means controlled by said operator for operating said switch to first 55 select one of said sources of current and then connect said automatic switch with said line while busy, means controlled by the busy condition of said line for preventing the establishment of a talking connection with said 60 party line, means for automatically establishing a talking connection with said line when it is again idle, means controlled by the idle condition of said line for connecting said selected source of ringing current there- 65 with, and means controlled by a called one of
- said stations for disconnecting said source of current and establishing a talking circuit with said operator.
6. In a telephone system, an automatic switch, a line relay for said switch, means for operating said line relay in response to a plurality of the digits of a called number, an auxiliary switch associated with said automatic switch, an operating magnet for said auxiliary switch, an operating magnet for 70 said automatic switch, means whereby the operation of said line relay in response to said digits, first operates only the operating magnet of said auxiliary switch, and thereafter operates the operating magnet of said 75 automatic switch.
7. In a telephone system, an automatic switch, a line relay for said switch, a called line, a plurality of sources of ringing current, an auxiliary switch for selecting one of 80 said sources, a pair of operating magnets for said automatic switch, an operating magnet for said auxiliary switch, means for operating the line relay of said switch in response to one digit of a called number to operate 85 the operating magnet of said auxiliary switch to select one of said sources of ringing current, and means for thereafter operating said line relay in response to a plurality of digits of the called number to operate said 90 pair of operating magnets to connect with said called line.
8. In a telephone system, an automatic switch, a line relay for said switch, a called line, a plurality of sources of ringing current, an auxiliary switch for selecting one of 95 said sources, a pair of operating magnets for said automatic switch, an operating magnet for said auxiliary switch, means for operating the line relay of said switch in 100 response to one digit of a called number to operate the operating magnet of said auxiliary switch to select one of said sources of ringing current, and means for thereafter operating said line relay in response to a 105 plurality of digits of the called number to operate said pair of operating magnets to find said called line and connect the selected source of ringing current thereto.
9. In a telephone system, an automatic switch, a line leading to said switch and individual thereto, a party line accessible to said switch, means for sending a plurality of series of impulses over said first line to said switch, five sources of ringing current, 110 a selecting device and means for operating it responsive to the first series of impulses to select any one of said sources of current without operating said switch, and means responsive to the succeeding series of impulses for operating the switch to connect with the said party line and signal the station thereon by means of the selected source of current.
10. In a telephone system, an automatic 115 120 125 130 switch, a line leading to said switch and individual thereto, a party line accessible to said switch, means for sending a plurality of series of impulses over said first line to said switch, five sources of ringing current, a selecting device and means for operating it responsive to the first series of impulses to select any one of said sources of current without operating said switch, and means responsive to the succeeding series of impulses for operating the switch to connect with the said party line and signal the station thereon by means of the selected source of current.

switch having a vertical and rotary motion, a line leading to said switch and individual thereto, a party line accessible to said switch, means for sending a plurality of series of impulses over said first line to said switch, a plurality of sources of ringing current, a step by step switch responsive to the first series of impulses to select one of said sources of current, a magnet responsive only to the next series of impulses to operate said switch vertically to select the group of lines in which the party line is located, and a second magnet responsive to the last series of impulses to rotate the switch to the desired party line and signal the station thereon by means of the selected source of current.

11. In a telephone system, an operator's position, an automatic switch, means for connecting said switch with said operator's position, an auxiliary switch individual to said automatic switch, a plurality of sources of ringing current, a line relay in said automatic switch, means for operating said line relay to cause said auxiliary switch to select 20 a source of ringing current in response to the first digit of a called number, means for operating said line relay thereafter responsive to a plurality of other digits to cause said automatic switch to establish connection 25 with the desired line, means for preventing the establishment of a talking connection with said line and the application of said selected ringing current thereto if busy, and means for establishing said talking circuit 30 when the said line becomes idle.

12. In a telephone system, an automatic switch, a line relay for said switch, means for operating said line relay in response to a plurality of digits of a called number, an auxiliary switch individual to said automatic switch, a differential relay in said automatic switch, an operating magnet for said auxiliary switch, an operating magnet for said automatic switch, means whereby 40 the operation of said line relay in response to said digits first operates the operating magnet of said auxiliary switch and thereafter operates the operating magnet of said automatic switch to complete a connection 45 to a called line, and means made operative 50 if said line is busy for energizing said differential relay.

13. In a telephone system, a plurality of sources of signalling current, each of said 55 sources supplying signalling current of a different frequency, a line, an automatic switch for connecting with said line, means for sending a plurality of series of impulses to said automatic switch, a step by step 60 switch individual to said automatic switch and operable independently thereof responsive to the first of said series of impulses for selecting one of said sources of current, and means whereby the remaining series of 65 impulses operate said automatic switch in

two planes to connect said source of current to said line.

14. In a telephone system, a line, an automatic switch, a plurality of sources of ringing current, means for sending a plurality of series of impulses to said automatic switch corresponding to digits in a called number, an auxiliary step by step switch associated with said automatic switch and operable independently thereof responsive to the first digit of said plurality for selecting one of said sources, and means for operating said automatic switch in response to the plurality of series of impulses corresponding to the remaining digits of said plurality to select said line and connect said selected source of ringing current thereto.

15. A telephone system including a called and a calling subscriber's line, a side-switchless connector switch, means for connecting said connector switch to said called subscriber's line, ringing current generators, a frequency selector for said connector switch, subscriber-controlled means for operating said frequency selector to select one of said ringing current generators, automatic means for intermittently applying ringing current from said selected generator to the called subscriber's line, and subscriber-controlled means for disconnecting the selected generator from the called line during a ringing period if the called subscriber answers during a ringing interval.

16. A telephone system including a calling and a called subscriber's line, a side-switchless connector switch adapted to be connected to the calling subscriber's line, ringing current generators, a frequency selector for said connector switch, subscriber-controlled means for actuating said connector switch and said frequency generator over the two sides of the calling subscriber's line in series for extending the connection to the calling subscriber's line and for selecting one of said ringing current generators, automatic means for intermittently applying ringing current from the selected generator to the called subscriber's line, and means responsive to the removal of the receiver at the called substation for instantly disconnecting or for preventing a reapplication of ringing current to the called subscriber's line depending upon whether the called subscriber responds during a ringing interval or a silent interval.

17. A frequency selecting connector comprising a connector switch and a frequency selector switch individual thereto, an operating magnet in each switch, a line relay in said connector switch, an operating circuit normally leading from the line relay to the connector switch magnet, and means effective when the connector is taken for use for transferring said circuit from the connector switch magnet to the frequency selector mag-

net and responsive to a series of impulses transmitted over said circuit for transferring the same back to said connector switch magnet.

- 5 18. A connector as set forth in claim 17 in which the ring cut-off relay constitutes the means for transferring the operating circuit from one magnet to the other as specified.
- 10 19. In a telephone system, party lines, an automatic switch having a vertical and rotary motion for selecting a party line, a trunk line leading to said switch and individual thereto, means for sending a plurality of series of impulses over said trunk line to said switch, an auxiliary switch in-
- 15

dividual to said automatic switch for selecting a party on any selected party line, a magnet for operating said auxiliary switch, a first and a second magnet for operating 20 said automatic switch in its vertical and rotary motions, respectively, and means for operating said auxiliary switch magnet responsive to the first of said series of impulses and for operating said first and second automatic switch magnets responsive to the next two of said series of impulses, respectively.

Signed by me at Chicago, Cook County, Illinois, this 5th day of February, 1918.

EMIL JACOBSEN.
